CLAIM

The ornamental design for a writing instrument, as
shown and described.

DESCRIPTION

FIG. 1 is a side elevational view of a writing instrument
showing my new design with the point retracted, the
opposite side being a mirror image thereof;
FIG. 2 is a left end view thereof;
FIG. 3 is a right end view thereof; and
FIG. 4 is a top plan view thereof with the point ex-
tended.

Fig. 1.

Fig. 2.

Fig. 3.

Fig. 4.
